UNITED STATES PATENT OFFICE.

CHARLES McC. CHAPMAN, OF MENDHAM TOWNSHIP, MORRIS COUNTY, NEW JERSEY.

DESIGN FOR AN EMBLEM.

43,352.

Specification for Design.

Patented Dec. 24, 1912.

Application filed September 11, 1912. Serial No. 719,880 $\frac{1}{2}$. Term of patent 7 years.

To all whom it may concern:

Be it known that I, CHARLES McC. CHAPMAN, a citizen of the United States, residing in Mendham township, Morris county, and State of New Jersey, have invented a new, original, and ornamental Design for Emblems, of which the following is a specification, reference being had to the accompanying drawing, forming a part thereof.

The drawing shown in Figure 1, is a face

view of my design, and Fig. 2 is a side elevation on a reduced scale of an article to which the emblem may be applied.

I claim—

The ornamental design for an emblem as shown.

CHAS. McC. CHAPMAN.
